UNITED STATES PATENT OFFICE.

WILLIAM G. LAMB, OF WATERLOO, IOWA, ASSIGNOR TO NATIONAL SAFETY DEVICES COMPANY, OF WATERLOO, IOWA.

SIGNALING APPARATUS.

Application filed April 27, 1926. Serial No. 104,944.

My invention relates to signaling apparatus, and the object of my improvement is to combine with such apparatus, a controller therefore having means for regulating a succession of signals to be produced by certain mechanisms thereof, and which means are also capable of operation alternatively in the voluntary production of a single or unregulated succession of signals, and which furthermore may be releasably locked in a certain position of continuous signaling when desired.

The above object I have accomplished by the means which are hereinafter described and claimed, and which are illustrated in the accompanying drawings, in which Fig. 1 is a diagrammatic elevation of a whistle signaling apparatus showing my improved controller associated therewith, parts being removed or broken away. Figs. 2 to 7 are detail views on larger scales of different devices of said apparatus. Fig. 2 is a front elevation of mechanism of the combination whose function is to effect automatically a series of predetermined intermittent actuations reactively, of the signal. Fig. 3 is a vertical medial transverse section thereof with parts removed. Fig. 4 is a side elevation of the devices shown in said Fig. 2. Fig. 5 is a vertical central section of the operating valve device for actuating the intermittently performing mechanisms of Figs. 2 to 4. Fig. 6 is a vertical central section of the differential valve device for controlling the communications of a bell motor made a part of the signaling circuits, and Fig. 7 is a vertical central transverse section of the rack quadrant controller of the apparatus.

Specifically, my invention herein constitutes an improvement upon the apparatus of A. I. Woodring, disclosed in Patent No. 1,600,527, and upon my own previous application for patent, Serial No. 100,656.

The automatic intermittently performing mechanism of the apparatus is the same as shown in said applications, operative to cause automatically a regulated succession of varying length signals as from a locomotive whistle, and will therefore be but briefly described.

The numeral 7 denotes a signal actuator adapted to be driven by means of compressed air or other fluid under pressure. It comprises a closed end cylinder, contain-

ing a packed plunger or imperforate piston 11 having a stem 6 protruding through an apertured bearing in one cylinder-head. The outer end of said stem 6 has a link connection 5 with a free end of a terminally pivoted arm 4 which may swing in one direction to press in a valve-stem 3 in a control valve contained in a chamber 2 of a whistle 1.

The piston 11 is resiliently reactively controlled by a coiled compression-spring 12 mounted between it and the adjacent cylinder-head. The opposite centrally apertured cylinder-head 10 seats a bored plunger-stem 20 whose bore 21 occasionally effects communication between the inner chamber 18 and the atmosphere. This chamber 18 is within a hollow part 9 which is removably mounted in the end of the cylinder 7 with its inner apertured end plugged at 14. In the part 9 opposite the plug 14 is a bearing opening for said stem 20 which has within the chamber 18 a valve-head 19 kept yieldingly upon its seat by a spring 15. An interspace between the part 9 and the cylinder-head 10 communicates by way of a by-pass 16 with the medial chamber 13 of the cylinder. The part 9 has an inlet-port 17 communicating between the chamber 18 and a conduit 102—100 having a control-valve 98 with a communication 97 to a conduit in communication with a source of fluid supply under pressure but not shown.

The middle interspace of the cylinder 7 at 13 has a port which is in communication with a conduit 83, and the latter communicates with the upper end of a differential valve chamber 84 whose larger upper chamber 88 contains an imperforate piston 85 of greater diameter than a valve-head 91 seated in a lower chamber upon a compression-spring 92 which keeps it yieldingly seated, the valves being connected by a stem 90 slidably fitted in a medial chamber 89, with the lower part of the stem narrowed above the valvehead 91 to communicate with a lateral port 86 controlled by a ball check-valve 87. The port 86 communicates by way of conduits 94, 95 and a valve-chamber 96 with said source of fluid under pressure. The lowermost chamber of the device 84 communicates by way of a port 93 with a conduit 99, and the latter is, by way of the valve-chamber 98, also in communication with said source of fluid under

pressure. While the valvular device 84 forms an adjunct to the whistle signaling apparatus, it will be no further referred to, being designed to control a bell motor not shown.

The cylinder 7 is pivotally suspended from a hanger coupling 8 fixed upon any convenient support. The cylinder 7 is integral with a casting which also includes 10 a lower cylinder 74, an intermediate spring-barrel 22, and a rear dash-pot chamber 48 not shown in detail. A rotatable shaft 23 is centrally mounted in the spring-barrel 22 and a coiled spiral spring 24 is end connected between said shaft and the inner wall of the spring-barrel.

Referring to Fig. 2, a discoidal face-plate 27 is mounted loosely upon the outer end of the shaft 23 and has its circumferential edge 20 cut away at 30 to provide a pair of like wide detents 28 succeeded by a pair of like narrower detents 29. A member is fixedly mounted upon the outer end of the shaft 23 and has a radial projection supplied terminally with a threaded pin which can be releasably inserted in any of an arcuate row of sockets in the plate 27 to connect them in a desired relative position of adjustment to properly tension the spring 24. Upon a 30 fixed bracket is mounted a rock-shaft 36 having a fixed depending arm 35. At 33 upon the lower part of said arm is pivotally mounted one end of a finger 32 whose movement downwardly is limited by a shoulder 34 on said arm 35. A small roller 31 is pivoted on the free end of the finger 32 and is in the path of movements to and fro of the detents 28 and 29.

A short upright arm 37 is fixed on the 40 rock-shaft 36 and contains a threaded contact-pin 38 in an apertured seat in its upper part which is alined with the reciprocable stem 20 in the cylinder-head 10 of the upper cylinder 7. Referring to Figs. 4 and 1, the 45 numeral 42 denotes an apertured bearing bracket to support an end of the shaft 36, and the numeral 39 denotes a sleeve which is loosely mounted on the shaft between the bracket part 42 and a sleeve fixed on the 50 rock-shaft which carries said arm 37. One end of the sleeve 39 is recessed at 40 through an arc of its circumference to be traversed by a fixed stud 41 projecting from the rock-shaft 36, which permits the stud to travel in 55 said recess limitedly before engaging the sleeve to rock it with the shaft.

Upon the loose sleeve 39 is fixed an upwardly projecting arm 43. A connecting-rod 63 is pivoted at its opposite ends to 60 and between the upper end of the arm 43 and the forward end of a curved arm 45, the rod 63 being continued beyond the arm 45 to be connected pivotally to one member of a bell-crank lever 107. The numeral 47 65 denotes an operating-valve for an imper-

forate piston 80 in the lower cylinder 74. The piston 80 has a stem 75 controlled yieldingly by a spring 76 connected thereto and engaging one end of one cylinder-head 77. The outer end of the stem 75 is pivoted at 70 78 to one end of a pitman 25, whose opposite end is pivoted at 26 to the face-plate 27.

The opposite end of the cylinder 74 has 75 a port 81 which is in communication with a delivery-port 61 of the valvular device 47 by way of a short conduit 73. The opposite inlet-port 62 of the valvular device is in communication by way of a conduit 101 with the conduits 100 and 97—95 supplying fluid 80 under pressure.

The body of the valvular device 47 contains upper and lower chambers 54 and 59 with a communicating passage 57. A plunger stem 56 in the chamber 54 traverses said 85 passage 57 slidably with its spaced wings and has a valve-head 58 closing the lower end of the passage and controlled by a spring 60 in the chamber 59. Above and vertically alined with the stem 56 is an 90 axially bored body with medial annular flange engaged by a compression spring in the chamber 54 to yieldingly keep the body in its upper position with the upper end of its bore 53 in communication with the 95 atmosphere. The upper end of the bore opens at the side of the upper diminished part of the body 52, and the upper end of the latter is below and in the path of downward rocking movement of a pressure finger or cam member 46 pivoted at 51 to an arched element 50 fixed upon the body 47. The member 46 is continued upwardly by said rock-arm 45, whose upper end is pivoted to the connecting-rod 63—64. A fixed stop 100 44 limits the swinging of the arm 43.

Referring to Figs. 1 and 7, the numeral 106 denotes a link between the lower member of the bell-crank lever 107 and the lower member of another bell-crank lever 105. The numeral 65 denotes the base of integral spaced rack quadrant members 66, of which one member has a medial notch 72 and near one end another notch 72a. A hand lever 68 is mounted pivotally between the members 66 on a pintle 67 and has a lateral projection over the notched member 66 which contains a downwardly opening socket 70 in which is seated a coiled compression spring 69 and a detent body 71 which is by the pushing of the spring kept in contact with the quadrant and to be propelled yieldingly into either notch thereof. A connecting-rod 104 is connected between the lever 68 and the upper member of the bell-crank lever 105. A bar spring 103 is fixed at one end on the base 65 and bears at the upper end against an edge of the lever 68 tending to 110 yieldingly propel it toward the medial notch 72 when first unseated and then released. 120 125 130

Operation. To automatically produce the highway crossing signal, which consists of two long succeeded by two short blasts of the whistle, the engineer simply swings over the lever 68 to the right and then releases it, the lever returning because of the reaction of the springs in the valvular device 47 which have been tensioned by his first action upon the lever and communicated 10 through the medium of said bell-crank levers and links to the cam-arm 45-46. In detail operation the said signals are produced as follows.

By means of the linkages above described, 15 the arm 43 is rocked to one side without rocking the rock-shaft 36, because of the loose pin and slot connections at 40 and 41. The arm 45 is also simultaneously rocked on its pintle to cause the cam 46 to press 20 downwardly the body 52 in the valvular device 47, closing the lateral opening of its bore 53 from the atmosphere. The upper spring 54 is compressed while the body 52 contacts with and presses down the valve- 25 stem 56 to open the valve 58, so that fluid under pressure passes from the port 62 by way of the inner passage 57 and chamber 55 to the outlet-port 61, the conduit 73 and port 81 into the lower cylinder 74 to shift 30 the plunger 80 while compressing the spring 76. The plunger-stem moves outwardly, and by means of its pintle 78 shifts a link- 35 arm 25 which is pivoted at 26 to the rockable face-plate 27, to rock the latter upwardly, the detents 28 and 29 swinging the arm 32 idly upwardly without swinging the arm 35. The shaft 23 is thus rocked in a direction to tension the coiled spring 24 in the spring-barrel 22. At this moment, as 40 the engineer releases the operating lever 68, and the lever returns to its medial vertical position, the connections return the cam-arm 45-46 to allow the springs 60 and 54 in the valvular device 47 to react, whereby 45 the valve 58 is closed and the body 52 is lifted to separate from the valve-stem 56 while the upper end of the bore 53 is again opened to the atmosphere. Residual fluid 50 under pressure in the device 47, the conduit 73 and the cylinder 74 is exhausted through the bore 53, so that the spring 76 in said cylinder may return by reacting, and thus the spring 24 in the spring-barrel 22 is permitted to also react to rock back the face- 55 plate 27. In rocking back the detents 28 and 29 in succession impinge upon the roller 31 of the arm 32, and swing the latter over together with the arm 35 by the arm 32 engaging the stop projection 34 on the arm 60 35.

This rocks the rock-shaft 36 and swings the upper arm 37 to cause the contact body 38 to push the slidable body 20 into the upper cylinder 7, closing the outer end of the bore 21, opening the valve-head while ten-

sioning the spring 15, while allowing fluid under pressure to pass from the port 17 from the conduits 102, 100, by way of the valve-chamber 98 and conduits 97 and 95 to the supply. The fluid passes the valve-head and by way of the by-pass 16 to the middle chamber 13, pushing out the plunger and stem 11-6, while compressing the spring 12. The linkages to the whistle device then sound the whistle. 75

When the residual fluid in the device 47 and the cylinder 74 is exhausted, the springs in both react, closing the passages of the device 47, and returning the plunger in the said cylinder rocking the face-plate 27 as 80 above described, and at the return of the latter the released arms 32 and 35 are swung back by the reaction of the spring 15 pressing out the body 20, the residual air in the chamber 13 of the cylinder 7 exhausting 85 through the bore 21, and the spring 12 then reacting to return the plunger 11. This completes the cycle of automatic signals.

For convenience of the engineer, I have supplied in combination with the above described apparatus, means whereby the whistle may be sounded at will without operating the automatic mechanisms. This consists of the rack quadrant 66 and its hand lever 68 as resiliently controlled, releasably held, and as linked to both the automatic mechanisms and to the operating valvular device 47 to actuate the mechanisms of the upper cylinder 7 independently either for one or more actuations of the whistle, or to 90 actuate the whistle continuously in case of need. 95

It will be seen, that when the engineer swings the hand lever 68 oppositely to the direction required to operate the automatic 105 signals, the valvular device 47 is not operated, and the shaft 36 not rocked, because of the loose pin and slot connection at 40 and 41, but the reversed direction of rocking of the arm 37 with its contact body 38 pushes in the body 20, so that in the manner above described, the mechanisms of the cylinder 7 are actuated to cause a single blast of the whistle 1, and this may be repeated at will, after each return of the lever 110 68. 115

In case a long continued whistle blast is required, at a time when the attention of the engineer must be given to some other duty, he may pull over the lever 68 until its 120 detent 71 engages with the farther notch 72^a, and thereupon the whistle will continuously blow until the detent is released by the forcible swinging back of the lever 68, as the rounded detent will ride out of the 125 rounded notch 72^a on the application of reasonable force applied to the lever.

My improvement, therefore, consists in adding to the combination of automatic and voluntary signaling means, of the further 130

function of permitting a continued blast of the whistle by releasably locking the lever 68 in the position for operating only the mechanisms of the upper cylinder 7, so that the engineer may relinquish the lever while attending to some other duty of simultaneous necessity and importance.

This control apparatus may be assembled very compactly according to a desired installation, and therefore may be mounted immediately adjacent to the controller of an electric car or the throttle-lever of a steam locomotive.

The linkages shown in Figs. 1 and 2 which connect the lever 68 to the rock-arm 37, may be varied in any desired way, without departing from the invention, and also any other suitable mechanical equivalents may be substituted for the lever 68 and rack 20 quadrant in performing the same functions, without departing from this invention.

It is also obvious, that said control apparatus may be associated with any species of signaling operating means, without the combination of other or automatic assemblages of mechanisms for producing predetermined series of signals, and yet contain the essence of this invention.

Having described my invention, what I claim as new, and desire to secure by Letters Patent, is:

1. In an apparatus of the character described, a signaling device, mechanism for actuating said signaling device with a predetermined series of actuations, said mechanism including limitedly movable coupled parts entrained between but unconnected with associated elements of the mechanism, an operating valve device also included in said mechanism, a quadrant having a medial notch and a notch near one end only, a lever pivoted abutting said quadrant having a controllable movable detent adapted to ride upon the quadrant to engage either notch, and connections between said lever and a movable part of the valve device and between the lever and one of said movably coupled parts, permitting the lever to be swung in one direction along the quadrant toward the end thereof having no notch to move the last-mentioned coupled part idly while simultaneously shifting said valve device part to actuate the valve and with it said mechanism for producing a series of signals by

the signaling device, the lever when swung to the opposite part of the quadrant beyond the medial notch causing idle movement of said valve device part while simultaneously moving said coupled parts to actuate a portion of said mechanism between them and the signaling device to operate the latter to produce a single signal, and in the latter movement of the lever when the detent thereof is engaged with the end notch of the quadrant, to produce a single signal by the signaling device of indefinite length.

2. In an apparatus of the character described, a signaling device, mechanism for actuating said signaling device with a predetermined series of actuations, said mechanism including limitedly movable coupled parts entrained between but unconnected with associated elements of the mechanism, an operating valve device also included in said mechanism, a quadrant having a medial notch and a notch near one end only, a lever pivoted abutting said quadrant having a resiliently controlled detent mounted movably thereon adapted to ride upon the quadrant to engage either notch, resilient means connected to said lever adapted to be placed under tension when the lever is moved in either direction away from said medial notch, and connections between said lever and a movable part of the valve device and between the lever and one of said movably coupled parts, permitting the lever to be swung in one direction along the quadrant to the end thereof having no notch to move the last-mentioned coupled part idly while simultaneously shifting said valve device part to actuate the valve and with it said mechanism for producing a series of signals by the signaling device, the lever when swung to the opposite part of the quadrant beyond the medial notch causing idle movement of said valve device part while simultaneously moving said coupled parts to actuate a portion of said mechanism between them and the signaling device to operate the latter to produce a single signal, and in the latter movement of the lever when the detent thereof is engaged with the end notch of the quadrant, to produce a single signal by the signaling device of indefinite duration.

In testimony whereof I affix my signature.

WILLIAM G. LAMB.
